TUBE SQUEEZER

Robert C. Barnes, 670 Edgebrook Drive, Houston, Tex.
Filed Aug. 30, 1961, Ser. No. 135,024
2 Claims. (Cl. 222—99)

The present invention relates to a device for facilitating the squeezing of material such as paste from a tube.

The primary object of the present invention is to provide a tube squeezer which is adapted to be used in conjunction with a conventional tube of material such as toothpaste, wherein the present invention can be manually actuated or operated in order to readily and conveniently eject or dispense a desired quantity of material from a tube and as for example the present invention can be used for dispensing toothpaste from a tube onto a toothbrush or the like.

Another object of the present invention is to provide a tube squeezer which includes a pair of members as well as a roller and wherein there is provided spring members for exerting pressure in the proper direction, and the roller being provided with an elongated recess or slot for selectively receiving therein end portions of the tube so that upon proper manual actuation of the device the material will be dispensed or ejected from the tube in the desired manner.

Another object is to provide a device of the character described that may be utilized speedily and with precision by even inexperienced operators.

Further objects and advantages are to provide improved elements and arrangements thereof in a device of the character described that is economical to produce, durable in form, and conducive to the most economical use of material and uniformity of members formed therefrom.

Still further objects and advantages will become apparent from the subsequent description and specification.

In the drawings:

FIGURE 1 is a top plan view showing the device in the starting position.

FIGURE 2 is a side elevational view with the parts in the position of FIGURE 1.

FIGURE 3 is a rear view of the tube squeezer of the present invention.

FIGURE 4 is an inside view illustrating certain construction details of the present invention.

FIGURE 5 is a sectional view taken on the line 5—5 of FIGURE 2.

FIGURE 6 is a sectional view taken on the line 6—6 of FIGURE 1.

FIGURE 7 is a fragmentary sectional view generally similar to FIGURE 6 but showing the parts squeezed together by the fingers.

FIGURE 8 is a view similar to FIGURE 7 but showing the members or elements in a different position.

FIGURE 9 is a vertical sectional view taken through one of the body members.

FIGURE 10 is a vertical sectional view taken through the other body member or element.

FIGURE 11 is a perspective view of one of the spring members.

Referring in detail to the drawings, the numeral 20 indicates the tube squeezer of the present invention which comprises a housing or casing that is indicated generally by the numeral 21, and the housing 21 includes upper and lower body members 22 and 23.

As shown in FIGURE 10 for example, the lower body member 23 includes a bottom wall 24 as well as a pair of spaced parallel side walls 25, and the member 23 further includes a back wall 26, and there are inwardly struck portions of the upper edge of the back wall 26 forming teeth 27 for a purpose to be later described.

2

As shown in the drawings, the side walls 25 include tapered portions 28 as well as enlarged opposed rounded portions 29, and there is provided opposed slots 30 in the rounded portions 29. As shown in FIGURE 10 for example, the longitudinal axes of the slot 30 are arranged parallel to the plane of the bottom wall 24.

The upper body member 22 includes a wall member 31, FIGURE 9, and the wall member 31 is shaped to include a generally flat section 32 as well as an arcuate section 33, and there is also provided a rearwardly disposed inwardly turned lip 34 which has extensions thereon that define or provide gripping fingers 35. The upper body member further includes a pair of spaced parallel side flanges 36 which have the same construction, and each of the side flanges 36 includes sections 37 of reduced size as well as sections 38 of increased size, and the enlarged sections 38 are arranged contiguous to the outer surfaces of the rounded portions 29 when the parts are properly assembled. The enlarged sections 38 are provided with opposed slits 39, and as shown in FIGURE 9 the longitudinal axes of the slits 39 are arranged at an angle with respect to the plane of the flat section 32. The numeral 40 indicates securing elements or pivot pins which extend through the registering slots and slits 30 and 39, and the pins 40 are connected to end portions of a roller 41, the roller 41 being positioned between the upper and lower body members 22 and 23, and the ends of the roller being interposed between the side walls 25 of the member 23. The roller 41 is provided with an elongated recess 42 for receiving therein the rear end portion 43 of a conventional tube 44, and the tube 44 is adapted to be provided with the usual neck portion 45, FIGURE 6.

As shown in the drawings, there is provided a pair 35 of similar spring members which are each indicated by the numeral 46, and the spring members 46 each include an intermediate coiled portion 47 which has an adjacent pin 48 extending therethrough, and there is provided hook portions 49 on the ends of the spring members 46 for engaging portions of the side walls and flanges of the body members.

The member 22 is provided with a lug 50 which extends inwardly from the lower end of the wall section 33, as shown in FIGURE 4, and the member 23 is provided with a similar lug 51 extending inwardly from the upper end of the back wall 26. The lugs 50 and 51 prevent the roller 41 from having the recess 42 caught upon either the back wall 26 or on the lower end of the wall section 33.

From the foregoing, it is apparent that there has been provided a device which is especially suitable for squeezing toothpaste or the like from a tube and while the present invention is described specifically for use in dispensing or discharging toothpaste or the like from a tube 55 such as the tube 44, it is to be understood that the present invention is not restricted to such use since it can be used in dispensing any suitable material from various types of tubes and the like.

In use, with the parts arranged as shown in the drawings, it will be seen that when the device is to be used, a tube such as the tube 44 is adapted to have its end portion 43 received in or seated in the recess 42 of the spool or roller 41, and then with the parts arranged as shown in FIGURE 6 for example, and with the cap or closure 65 on the neck 45 removed, when it is desired to dispense a quantity of toothpaste or the like from a tube such as the tube 44, finger pressure is applied to the members 22 and 23 so as to cause the members 22 and 23 to be moved together from the position shown in FIGURE 6 to the position such as that shown in FIGURE 7. As the parts move to the position of FIGURE 7 from the position of FIGURE 6, the teeth 27 dig into or engage a portion

of the roller 41 so as to cause the roller or spool 41 to start to turn whereby a portion of the tube 44 will be rolled on the spool 41 so that the toothpaste or the like will be dispensed out through the end portion 45. When manual pressure is released on the members 22 and 23, the spring members 46 return the parts in the position shown in FIGURE 7 to a position such as that shown in FIGURE 6, so that the device is in position ready to be subsequently used in the same manner by additional paste yet to be dispensed onto a toothbrush or the like. It is 10 to be noted that when manual pressure on the members 22 and 23 is released, the teeth 27 engage a portion of the roller or tube so as to act as a brake in order to prevent the spool or roller from unwinding, so that in effect a ratchet mechanism is provided. The slits 39 and the slots 30 are arranged at a proper angle so as to permit the necessary expansion between the members 22 and 23 to take place as the additional portions of the tube are wound on the spool 41, and also these slits and slots have portions of the pin 40 extending therethrough and provide sufficient clearance for the necessary movement to take place whereby the desired action can be accomplished.

Initially as the teeth 27 and gripping fingers 35 engage outer peripheral portions of the roller 41, but as the device is continued to be actuated, portions of the flattened tube are wrapped around the roller 41 so that the teeth 27 and gripping fingers 35 will engage the portion of the tube on the spool 41 in order to bring about the necessary gripping and ratchet action as well as to insure that the parts will not turn in the wrong direction or accidentally slip.

The parts can be made of any suitable material and in different shapes or sizes.

With further reference to the springs 46, there is provided a hook portion or slot portion 29' in the rounded section 29, FIGURE 10, and this hook portion 29' is provided on top of the portion 29 to hold an end of a spring 46 and this is necessary to force the member 23 forward on releasing of the squeezing pressure. The other end of the spring as at 49 contacts the member 22 at its rear ends in the grooves formed where the portions 34 and 35 meet. This is necessary to keep the parts 22 and 23 from opening to the limits of the slot 39.

5 It also keeps the gripping fingers 35 in close contact with the roller or tube.

Minor changes in shape, size and rearrangement of details coming within the scope of invention claimed may be resorted to in actual practice, if desired.

What is claimed is:

1. A tube squeezer comprising a housing including upper and lower body members, said lower body member comprising a bottom wall, a pair of spaced parallel side walls and a back wall, spaced apart teeth on the upper edge portions of said back wall, said side walls each having the same construction and each including tapered portions and opposed rounded portions, there being opposed slots in said rounded portions; said upper body member comprising a wall member including a generally flat section and an arcuate section, an inwardly turned lip on the rear of said wall member, extensions on said lip providing gripping fingers, said upper body member further including a pair of spaced parallel side flanges which have the same construction and which include sections of reduced size and enlarged sections, said enlarged sections being arranged contiguous to the outer surfaces of said rounded portions, there being opposed slits in said enlarged sections, a roller positioned between said upper and lower body members and said roller being interposed between the side walls of said lower body member, pivot pins extending through said slots and slits and connected to the ends of said roller, there being an elongated recess in said roller for receiving an end portion of a tube being squeezed, and a pair of spring members each including an intermediate coiled portion interposed between a side wall and flange and said coiled portions having adjacent pins extended therethrough, and hook portions on the ends of said spring members engaging portions of the side walls and side flanges.

2. The structure as defined in claim 1 wherein the longitudinal axes of said slots are parallel to the plane of the bottom wall, and wherein the longitudinal axes of the slits are arranged at an angle with respect to the 40 plane of the flat section of the wall member.
